SECOND ELEVATOR FOR TYPOGRAPHICAL MACHINES

Clay E. Murray, Davenport, Iowa, assignor to Linograph Corporation, Davenport, Iowa, a corporation of Delaware

Application August 16, 1937, Serial No. 159,334

12 Claims. (Cl. 199—37)

The present invention relates to that kind of typographical machines in which one line of type is composed and cast at a time, and relates more particularly to the second elevator mechanism of such a machine. Among the objects of this invention are to conserve space; to provide a machine which will have exceptionally wide magazines for a given overall width of machine; to provide, in a machine of the character indicated, a safety mechanism which will prevent breakage in event the second elevator becomes blocked and unable to move; and such further objects, advantages, and capabilities as will hereafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 represents a front elevation of a fragmentary portion of a machine embodying my invention;

Fig. 2 represents the same structure in a different portion of its operative cycle; and

Fig. 3 represents the same structure in a still different portion of its operative cycle.

The face plate 1 is shown as having a projection 2 at one corner thereof upon which the second elevator 3 is pivotally mounted at 4 and 5. The second elevator comprises a head 6 and a pair of arms 7 and 8 by which the head is supported and actuated. An arm 9 connects the arm 8 to the link 10 so that power may be transmitted to the elevator to cause the same to swing in a substantially vertical plane in a direction parallel to the magazines. The head 6 and the lower arm 7 are pivotally connected at 11, while the head is pivotally connected to the upper arm 8 at 12. A pair of fingers 14 rise from the head 6 and are slightly notched to receive the cross pin 12 projecting from the sides of the arm 8. Springs 13 are secured to the fingers 14 and are somewhat bent to cooperate with the pivot or cross pin 12 and the fingers 14.

A screw 15 furnishes an operative connection between the arms 8 and 9 and makes possible the adjustment of the vertical swing of the elevator. A spring 16 furnishes means between the crank arm 9 and the arm 8 so that there will not be lost motion between these parts.

The matrices and space bands are carried from casting position to the upper transfer position by the elevator slide 17 provided at its upper end with the elevator jaws 18. They are pushed forward into the intermediate box 19 by the pusher 19a. The space bands are indicated at 20 while

the matrices are shown in dotted lines at 21. The ears of the space bands are longer than those of the matrices and, therefore, the latter may be lifted out of the intermediate box 19 by the head 6, as shown in Fig. 2. Before the matrices and space bands are transferred from the elevator jaws 18 to the intermediate box 19, the head 6 assumes the position shown in Fig. 1 and is ready to receive the matrices 21, the space bands 20 being separated from the matrices by suitable mechanism, not shown. When the link 10 is pulled downwardly from the position shown in Fig. 1 toward that shown in Fig. 2, the head 6 is elevated but it is always maintained in a position parallel to the position which it occupies in Fig. 1. As the head 6 moves upwardly, the matrices 21 are lifted away from the space bands 20 and the latter are moved to the right by the shifting means 22 connected to the pusher 19a by the link 19b to be discharged into the space box 23. Here they are ready for use in the setting up of a subsequent line.

Since the pivots 4 and 5 are fixed and are the same distance apart as the pivots 11 and 12, and since these four pivots define a parallelogram, a plane defined by the axes of the pivots 11 and 12 must maintain a position of parallelism with any other position which this plane assumes. Therefore, the head 6 must, at all times, remain parallel to any position which it may occupy at any time during its course of travel.

If the head 6 should become stuck or jammed for any reason, when in its lowermost position, so that it cannot rise when the link 10 is pulled downwardly, then the downward pull would cause the arm 8 to turn on its pivot 5, the pivot 12 being released from between the fingers 14 and the springs 13. Thus, breakage of the machine because of the immovability of the head will not result. The operation of the machine will then be stopped and the cause of the trouble can then be located and removed.

When the second elevator reaches its uppermost position, illustrated in Fig. 3, the distributor shift lever 24 turns about its pivot, located at a point below any part of Fig. 3, and pushes the link 25 to the right to cause the head 26 to engage the matrices and shove them on to the bar 27 of the distributor box from which they pass to the distributor mechanism at the right and are re-distributed by the screw 28 to the magazine 29. This distribution is well understood by those skilled in the art and does not need to be referred to in further detail herein.

If the head 6 fails to seat completely upon the intermediate box 19, then the arm 7 will fail to engage screw 30 to cause lifting of the lever arm 31. Unless this is lifted, the pusher will not be released so that the matrices and space bands can be moved into the intermediate box 19. Guide 60

members 32 and 33 cooperate with the projections 34 and 35 on the head 6 to insure that the matrix supporting bar 36 of the head will line up with bar 27.

5. It is of course understood that the specific description of structure set forth above may be departed from without departing from the spirit of my invention as set forth in this specification and the appended claims.

10. Having now described my invention, I claim:

1. In a typographical machine, a support, a matrix elevator pivotally mounted thereon, said elevator comprising a head and a compound head-lifting arm, said arm comprising a pair of individually pivoted arms mounted on said support for united or separate swinging motion in a substantially vertical plane, said head having fingers projecting therefrom and pivotally connected to the free ends of said individually pivoted arms, the upper one of said pair of arms having a crank arm whereby force may be applied to it to cause it to turn about its pivotal connection to the support, the pivotal connection of the upper arm to said fingers being such as to normally cause the head to swing with said upper arm but such as will permit the head and arm to separate if the head becomes locked in any manner and unable to swing with the arm.

2. A structure as defined by claim 1 in which the pivots of said compound arm define a parallelogram so that the head, during its movements, will always occupy positions of mutual parallelism.

3. In a typographical machine, a support, a matrix elevator pivotally mounted thereon and swinging substantially in a plane defined by a magazine of the machine, said elevator comprising a head and a compound head-lifting arm, said arm comprising a pair of individually pivoted arms mounted on said support for united or separate swinging motion in a substantially vertical plane, said head having fingers projecting therefrom and pivotally connected to the free ends of said individually pivoted arms, an intermediate box, and a distributor box, said head cooperating with said boxes, and said compound arm carrying said head from a position in which it cooperates with one of them to a position in which it cooperates with the other.

4. In a typographical machine, supporting means for the movable mechanisms of the machine, an intermediate box carried thereby, a distributor box, a matrix transferring head cooperating with said boxes, a parallelogram arm having two pivots connecting it to said supporting means and two connecting it to said head, mechanism for swinging said arm to raise and lower said head, the arm swinging in a plane substantially parallel to the plane of a magazine in position for use.

5. A structure as defined by claim 4 in which the distributor box is located above, and substantially in the same plane as, the intermediate box, but laterally in that plane away from the center of the machine.

6. In a typographical machine, supporting means provided with a pair of pivots for an elevator arm, an intermediate box, an elevator head cooperating with said box and having openings to cooperate with said elevator arm, an elevator arm comprising a pair of arms, each cooperating with one of said pivots, the opposite end portions of said arms cooperating with said head, said

arms being constructed and arranged to swing in a direction substantially parallel to the planes of the machine magazines, said head having pivotal connection with the free ends of said pair of arms, the four pivots of the arms defining a parallelogram, and the head being held by the arms, at all times, in positions which are mutually parallel, and, when carried upwardly by the arm, swinging laterally away from the center of the machine in a plane substantially parallel to the planes of the magazines.

7. A typographical machine having supporting means and substantially vertically positioned magazines, said supporting means extending laterally from the magazines, an elevator arm pivotally mounted on said supporting means and swinging in a substantially vertical plane parallel to the planes of the magazines, an elevator head carried by said elevator arm, an intermediate box adjacent the magazines, said head cooperating with said box and being carried away from the center of said magazines as it is raised by said arm.

8. In a typographical machine, an elevator arm comprising a pair of arms pivotally mounted on the machine frame, a crank arm connected to the upper one of said arms for operation thereof, an elevator head carried by the free end of said elevator arm and pivotally connected to the free end of each of said pair of arms, said head transmitting force from said upper arm to the lower arm to cause turning thereof about its connection to the machine frame, the connection of the head to the upper arm being a yielding connection which may, upon application of excessive force, separate, permitting the head to remain in fixed position and the upper arm to swing freely upwardly.

9. In a typographical machine, an intermediate box, an elevator head cooperating therewith, an elevator arm pivotally connected to said head by a slip connection, said arm being pivotally connected to the machine at a point remote from said head, and said arm having a crank arm by which force may be transmitted to the elevator arm to cause turning thereof about its pivotal connection to the machine and raising of the head, the slip connection yielding in event of excessive resistance by the head against vertical movement thereof, whereby to permit the arm to swing independently of the head.

10. In a typographical machine having an elevator arm pivotally mounted upon the machine frame, an elevator head connected to said arm by a disconnectible slip connection adapted to yield upon application of excessive force and permit separation of the head and arm so that the head may remain stationary while the arm swings upwardly.

11. In a typographical machine having a supporting frame and magazines, an elevator arm mounted on said frame to swing vertically in a plane substantially parallel with the magazines.

12. In a typographical machine having a supporting frame and magazines, an elevator arm mounted on said frame to swing vertically in a plane substantially parallel with the magazines, said elevator arm having a head and said head, in its lowermost position, being adjacent the magazines and, as it swings upwardly, swinging away from the center of the magazines.
